US0D1069130S

(12) United States Design Patent (10) Patent No.: US D1,069,130 S
(45) Date of Patent:  Apr. 1, 2025

(54) NURSING CAP

(71) Applicant: Tecnologia Ospedaliera S.r.l., Sona (IT)

(72) Inventor: Emma Sevignani, Sona (IT)

() Term: 15 Years

(21) Appl. No.: 35/516,238

(22) Filed: Mar. 21, 2022

(80) Hague Agreement Data

Int. Filing Date: Mar. 21, 2022

Int. Reg. No.: DM/222206

Int. Reg. Date: Mar. 21, 2022

Int. Reg. Pub. Date: Feb. 10, 2023

(51) LOC (15) Cl. 24-04

(52) U.S. Cl.

USPC D24/189

(58) Field of Classification Search

USPC D24/109, 155, 188, 189, 190, 193-200, D24/205; D29/100, 101.3

CPC .. A41B 9/12; A61J 11/006; A61J 11/00; A61J 11/0035; A61J 13/00
